COOLED BOILER CASING

David M. Schoenfeld, New York, N. Y., assignor to
 Combustion Engineering Company, Inc., New
 York, N. Y.

Application January 1, 1942, Serial No. 425,281

7 Claims. (Cl. 110—56)

This invention relates to improvements in steam boiler casings and particularly to casings for boilers operating under forced draft, such as marine boilers.

In marine boilers, especially those in ships that may encounter poisonous or noxious gases, it has been found desirable where air is drawn from outside the ship for combustion within the boiler furnace to isolate it from the air within the boiler room. Ordinarily the boiler has been surrounded by a gas tight casing separated from the setting to provide space into which the combustion air is delivered to circulate around the setting and then pass via the burner openings into the furnace. Where the air has been heated by flue gases in an air heater, it has heretofore been usual to pass heated air from the heater through the space between casing and boiler. Because of the arrangement of the connection between the air preheater and the casing this air took the path of least resistance to the burners, thereby short-circuiting some portions of the setting so that air under pressure was not present to seal all parts of the boiler setting where gases might flow outwardly into the fire room. Because of its temperature this concentration of preheated air has required the outside of the casing to be heavily insulated so as to maintain its outer wall at a satisfactory temperature.

An object of this invention is to provide an improved gas tight casing spaced from a boiler setting in combination with an air heater. This and other objects will be best understood upon consideration of the following description of an embodiment of the invention when read in conjunction with the accompanying drawings, illustrating the invention applied to a marine boiler.

Figure 1 is a horizontal sectional view through a marine boiler on line 1—1 of Fig. 2;

Figure 2 is a diagrammatic elevation on line 2—2 of Fig. 1;

Figure 3 is a diagrammatic elevation on line 3—3 of Fig. 1;

Figure 4 is a sectional elevation of a portion of the boiler unit on line 4—4 of Fig. 1 showing a cross section through the air heater.

Referring to Fig. 1, the boiler comprises a furnace 10 having openings 11 to mount burners projecting through one side wall 33 for introducing fuel and air. The products of combustion pass over banks 12, 13 of steam generating tubes and an intervening superheater 14 to the boiler offtake 15 at one end of the boiler. Located in the offtake is an air heater 16 (Fig. 4), comprising tubes 20 connected into upper

and lower tube sheets 21, 22 and mounted vertically so that gases from offtake 15 pass through the tubes into the boiler flue 23. A baffle 24 intermediate the tube sheets 21, 22 serves to divide the usual transverse air passageway into an upper pass 25 and a lower pass 26 connected serially at one end by a conduit 27. The air for combustion is delivered to the air inlet chamber 28 by a fan, not shown, and the greater part passes through the passes 25, 26 to the air outlet chamber 29 and thence via a conduit 30 (Fig. 2) to the burner openings 11.

As shown in Fig. 1 the boiler is enclosed in a composite wall 31 extending from the offtake 15 where the air preheater 16 is located across the front or burner side, around the end opposite the offtake and back thereto across the rear wall and also over the top of the boiler. The composite wall is made up of an inner refractory lining 32 backed by insulation 33 and a steel casing 34. Spaced outwardly from the wall 31 is a second or outer wall casing 35 lined with insulation and also extending around the three sides and also over the top of the boiler. The casings 31, 35 and particularly the latter which forms the outer wall, are made gas-tight so that no gas that may be between them can enter the boiler room.

As may be seen in Fig. 2 the space 39 between the inner and outer walls on the burner side of the boiler is subdivided into several conduit-like channels by partitions 40, 41 extending along and between these walls 31, 35 from the offtake 15 at the vertical location of the baffle plate 24 and lower tube sheet 22, respectively, of preheater 16. These partitions terminate short of the end walls opposite the offtake and are interconnected by a plate 42 thereby forming a vertical channel 43 placing the upper conduit 44 in communication with the lower conduit 45, the intervening conduit 30 being connected at one end with the preheater outlet 29 for directing heated air to the burner openings 11 as previously mentioned. The upper channel 44 receives cool air from inlet chamber 28 of the air preheater 16 through an opening 46 (Figs. 2 and 4) at the lower corner of the inner side wall 47 (Fig. 2) of the preheater. The bottom of the heated air outlet chamber 29 overlies one end of conduit 45 and has holes 48 for air to flow from conduit 45 into chamber 29 and thence to the burner openings 11 via conduit 30.

Some air from the channels 44, 45 and their intermediate branch 43 flows through the space 50 between the inner and outer end walls that

extends across the top and end of the boiler to the side wall opposite the burner openings 11. At the side opposite burner openings 11 a partition 49, extending horizontally (Fig. 3) from the end of the boiler opposite the offtake 15 at a vertical location intermediate the baffle 24 and lower tube sheet 22 and a parallel partition 51 below this tube sheet form three conduit channels 52, 53, 54. As may be noted in Figs. 2 and 3 these partitions continue at 49a, 51a across the space 50 between the inner and outer walls at the end opposite the boiler offtake. Each of the channels 52, 53, 54 communicates through holes 55, 56 and 57 respectively, with conduit 27 which directs the air from the first to the second pass 26 of the air heater. In operation cool air is delivered to inlet chamber 28 of the preheater 16, the major part passing through to the outlet chamber 29 and thence via conduit 30 directly to the air registers of burner openings 11. Because of the relatively high temperature of this preheated air, the insulation on the outer casing adjacent conduit 30 will be relatively thick. A minor part of the air passes from inlet chamber 28 through opening 46 (Figs. 2 and 4) into the upper channel 44 of the front wall, thence via channels 43 and 45 and through holes 48 into the outlet chamber 29. Some of this air passes from channels 44, 45 and branch channel 43 through the space across the top and end wall (Figs. 2 and 3) into the three channels 52, 53, 54 of the wall opposite burner openings 11 and thence through the respective holes 55, 56, and 57, into the conduit 27 connecting the first and second passes of the heater. Since the part of the air passing around the boiler between the inner and outer walls is heated only to the extent that it absorbs heat as it cools the setting, the insulation on the outer casing adjacent the channels through which this air circulates need not be as thick as that adjacent the hot air conduit 30 which receives preheated air.

The circulation of air through the channels is caused by the differences in pressure existing between the inlet chamber 28 and the conduit 27 at the end of the first pass and the outlet chamber 29. The amount of air flowing to seal and cool the setting may be determined by the area of the holes 48, 56, 57 between the respective channels and the air heater chambers 27, 29, or by other known means, such as dampers 60, 61 at opening 46 and in conduit 27. Because of this control over the distribution of the air around the setting and the use of cold air, the space between outer casing and setting wall may be reduced in depth and less outer insulation utilized thereby effecting a saving in space and weight.

What I claim is:

1. In a steam boiler having a furnace including a front wall formed with openings for introducing air into the furnace, and a gas offtake at one end of the furnace; a casing around and spaced from said boiler to form an air chamber; a multi-pass air preheater so arranged in said offtake that its air inlet and outlet are located adjacent the front wall of said boiler and communicate directly with the portion of said air chamber along said front wall at the offtake end thereof; partition means in said casing extending along said front wall to form a conduit leading through said air chamber from the outlet of said preheater to said front wall openings; and means closing said conduit adjacent the end wall opposite said offtake.

2. In a steam boiler having a furnace including a front wall formed with openings for introducing

air into the furnace, and a gas offtake at one end of the furnace; a casing around and spaced from said boiler along the front and rear walls and extending over the top and across the end wall opposite said offtake whereby an air chamber is formed; a multi-pass air preheater so arranged in said offtake that its air inlet and outlet are located adjacent the front wall of said boiler and communicate with the portion of said air chamber along said front wall at the offtake end thereof and so that an interpass duct of said preheater is located adjacent said rear wall and communicates with the portion of said air chamber along the rear wall at the offtake end thereof; partition means extending along said front wall in said air chamber to form a conduit leading through said air chamber from the outlet of said preheater to said front wall openings; and means closing said conduit adjacent the end wall opposite said offtake.

3. In a steam boiler having a furnace including a front wall formed with openings for introducing air into the furnace, and a gas offtake at one end of the furnace; a hollow wall extending along the front of the boiler to form an air chamber; a multi-pass air preheater so arranged in said offtake that its air inlet and outlet are located adjacent the front wall of said boiler and communicate directly with the portion of said air chamber along said front wall at the offtake end thereof; partition means in said casing extending along said front wall to form a conduit leading centrally through said air chamber from the outlet of said preheater to said front wall openings; a partition closing said conduit adjacent the end wall opposite said offtake, said partition being spaced from said end wall to form a channel for air to flow from the part of said air chamber above said conduit to the part therebelow.

4. In a steam boiler having a furnace including a front wall formed with openings for introducing air into the furnace and a gas offtake at one end of the furnace; a casing around and spaced from said boiler along the front and rear walls and extending over the top and across the end wall opposite said offtake whereby an air chamber is formed; a multi-pass air preheater so arranged in said offtake that its air inlet and outlet are located adjacent the front wall of said boiler with an interpass duct thereof located adjacent the rear wall of the boiler; means forming a conduit leading centrally through said air chamber to said front wall openings; means placing said conduit in communication with the outlet of said preheater; means placing the portion of the air chamber along said front wall above said conduit in communication with the said preheater inlet; a partition in said air chamber spaced from the end wall opposite said offtake closing said conduit and forming a passage from the portion of said air chamber along said front wall above said conduit in communication with the portion thereof below said conduit; and means placing the said last portion of said air chamber in communication with said conduit in advance of said front wall openings.

5. In a steam boiler having a furnace including a front wall formed with openings for introducing air into the furnace, a gas offtake duct communicating with one end of the furnace, heat absorbing elements interposed between said furnace and said offtake, and an air heater having a cold air inlet and hot air outlet; an inner setting wall enveloping said furnace and said elements; an outer wall spaced from said inner wall to form

an air chamber; partitions dividing said chamber into channels for circulating cool air about the setting and into a conduit arranged to convey heated air from said heater outlet to said front wall openings; means delivering cool air to said air heater and to said channels; and means connecting said channels to the air passages of said air heater at locations beyond its air inlet in the direction of air flow therethrough; and means for controlling the flow of air through said respective channels into said air heater.

6. In a steam boiler having a furnace including a front wall formed with openings for introducing air into the furnace, and a gas offtake at one end of the furnace; means forming a casing around and spaced from the boiler along the front and rear side walls and extending over the top and across the end wall opposite said offtake whereby an air chamber is formed; a multi-pass air heater so located in said offtake that its cold air inlet and hot air outlet are disposed adjacent the front wall in communication with the air chamber therealong; partitions in said casings along said front wall in said air chamber dividing said chamber into a conduit in said front wall for conveying hot air from said heater out-

let to said burners and channels for conveying cold air around said conduit to the outlet of said air heater thence to said front wall openings.

7. In a steam boiler having a furnace including a front wall formed with openings for introducing air into the furnace, and a gas offtake at one end of the furnace; a multi-pass air heater in said offtake having a cold air inlet and a hot air outlet adjacent said front wall and an interpass duct adjacent the rear boiler wall; means forming an air chamber encasing said boiler along the front and rear walls and extending over the top and across the end wall opposite said offtake; partitions dividing said chamber to form front wall channels and communicating roof, end and rear wall channels for circulating air therethrough; means closing the end of a channel on said front wall to form a conduit leading through said chamber conveying hot air from said heater outlet to said front wall openings; means delivering cold air to the inlet of said air heater and another channel in the front wall; means connecting the roof, end and rear wall channels to said inter-pass duct of said air heater and said front wall channel to said air heater outlet.

DAVID M. SCHOENFELD.
